UNITED STATES PATENT OFFICE.

FRANKLIN R. WHITE, OF WATERBURY, CONNECTICUT, ASSIGNOR TO THE PLATT BROTHERS AND COMPANY, OF WATERBURY, CONNECTICUT, A CORPORATION OF CONNECTICUT.

BUTTON.

1,053,260.

Specification of Letters Patent. Patented Feb. 18, 1913.

Application filed December 16, 1910. Serial No. 597,694.

To all whom it may concern:

Be it known that I, FRANKLIN R. WHITE, a citizen of the United States, and a resident of Waterbury, in the county of New Haven and State of Connecticut, have made and invented certain new and useful Improvements in Buttons, of which the following is a specification.

My invention relates to buttons designed to be permanently attached to a garment by means of a staple, the prongs of which are bent or clenched about a bar in the act of securing the button to a garment, and the object thereof is to provide an improved button of the type above specified which may be easily manufactured, which will be strong and effective for the purpose for which it is designed, and one which is so formed as to be readily used with certain types of button setting machines, which, however, form no part of the invention disclosed and claimed in this particular application.

With the objects above enumerated in view, my invention consists in the improved button hereinafter described, illustrated in the accompanying drawing, and claimed at the end of the specification.

In the drawing wherein the preferred embodiment of my invention is illustrated; Figure 1 is a view showing a plan of my improved button. Fig. 2 is a view showing the same as seen from the bottom. Fig. 3 is a view showing a cross-section upon a plane indicated by the line 3—3, Fig. 1. Fig. 4 is a similar view, the button being shown as secured to a garment by means of a fastening staple. Fig. 5 is a view showing the button in plan and secured to a garment, as in Fig. 4. Fig. 6 is a view showing the button in side elevation. Fig. 7 is a view showing a cross-section upon a plane indicated by the line 7—7, Fig. 6. Fig. 8 is a view showing a reinforcing member in perspective, and Fig. 9 is a perspective view showing a staple whereby my improved button is secured to a garment.

In the drawing, 1 is the enlarged head of the button, and 2 is the hub or shank portion thereof through which the button is secured to the garment by means of a staple 3. The head and hub are commonly formed from sheet metal by means of dies, and the bottom of the hub is, in practice, formed integrally with the upper portion thereof and

cut out in part by a suitable punch to form an inwardly extending ledge 4, and a bar 5 extending across the lower end of the hub. Within the hub is a reinforcing member 6 having a transverse bar 7, said member being located within the hub with its bar overlying the bar 5 of the hub, and with its outer edge resting upon the inwardly extending ledge or flange 4. The reinforcing member is formed as a disk, portions thereof being cut out to provide the transverse bar 7. The staple 3 has two prongs which, in the act of securing the button to a garment, are bent and clenched about the transverse bars 5 and 7, as shown in Figs. 4 and 5, the prongs being bent by means of a suitable anvil of the mechanism (not shown) by which the button is secured to the goods, which anvil enters the hub through an opening 8 provided for that purpose in the button head.

For the purpose of adapting my improved button for use in certain types of button feeding machines having two parallel guides closer together than the maximum diameter of the shank portion 2, I provide two flat portions 9—9 upon the hub as shown in Fig. 7, these flat portions being shown as formed by forcing diametrically opposite portions of the wall of the hub inward; these flattened sides or portions of the wall perform the further function of retaining the reinforcing member 6 in place, as the metal thus forced inward lies immediately over the periphery of the said reinforcing member. These flattened portions or sides of the hub extending from the head of the button to within a short distance of the lower end of the hub, thereby form an outwardly extending flange 10 at the base of the flattened sides, which insure the holding of the button in the groove and between the tracks forming a race-way of the button setting mechanism, (not shown).

From the foregoing it will be understood that by forming a button with a hub having two flattened sides, the button may be fed to the button-setting mechanism with its bar 5 extending cross-wise of the chute through which the button is fed to the button-setting mechanism, thus insuring the proper relative positions of the said bar and fastening staple, which would not be the case if the button were provided with a hub of cylindrical shape and permitting it to turn or

rotate during the feeding of the same to the button-setting mechanism. Furthermore, by forming the flanges 10 on the lower end of the hub, and which fit under tracks or guides in the slot of the button-setting machine, it will be seen that the button is prevented from becoming accidentally disengaged from said slot.

From the foregoing it will be understood that my invention is exceedingly simple in construction, and, as I have found from actual test, effective in overcoming the difficulties heretofore experienced with this type of button, as the pointed ends of the fastening staple are effectively prevented from being bent outwardly and off of the base of the button prior to piercing their way through the same. Furthermore, by gradually increasing the diameter of the prongs of the staple from the pointed end toward the base instead of having them of uniform diameter, as heretofore, a fastener is produced, which will, with certainty, pierce its way through the bottom of the button and avoid the liability of bending or becoming distorted.

Having thus described my invention I claim and desire to secure by Letters Patent:

30 1. A button having an enlarged head provided with a central opening, and a hub projecting from said head and through which the button is secured to a garment, said hub having an inwardly extending flange at its lower end and a bar extending across the lower end of the said hub, and said flange and bar being integral with said hub, and a reinforcing member adapted to

rest upon said flange and having a diametrically extending bar adapted to register with said first mentioned bar, the wall of said hub being forced inward at two sides intermediate the ends thereof, to thereby form inwardly extending projections above said reinforcing member, and the lower end of said hub being of greater diameter than the minimum diameter of the hub at the flattened portion thereof.

2. A button having an enlarged head provided with a central opening; a hub projecting from said head and through which the button is secured to a garment, said hub being cylindrical in form and having an inwardly extending flange at its lower end and a bar formed integrally with said flange and extending across the lower end of said hub; said flange and bar being integral with said hub and a reinforcing member annular in form and adapted to rest upon said flange, and having a diametrically extending bar adapted to register with said first mentioned bar, said hub having two flat sides intermediate the ends thereof to thereby form inwardly extending projections above said reinforcing member, and the lower end of said hub being of greater diameter than the minimum diameter of the hub at the flattened portion thereof.

Signed at Waterbury, in the county of New Haven and State of Connecticut, this 76 second day of December A. D. 1910.

FRANKLIN R. WHITE.
